(57) CLAIM

The ornamental design for an article carrier, as shown and described.

DESCRIPTION

FIG. 1 is a front exterior perspective view of an article carrier, in accordance with the ornamental design, illustrated in its closed configuration;

FIG. 2 is a front view thereof;

FIG. 3 is a rear view thereof;

FIG. 4 is a side view thereof;

FIG. 5 is a top view thereof;

FIG. 6 is a bottom view thereof;

FIG. 7 is a front view similar to that of FIG. 2, but with the article carrier illustrated in its open configuration;

FIG. 8 is a front exterior perspective view of an alternate embodiment of an article carrier, in accordance with the ornamental design, illustrated in its closed configuration;

FIG. 9 is a front view thereof;

FIG. 10 is a rear view thereof;

FIG. 11 is a side view thereof;

FIG. 12 is a top view thereof;

FIG. 13 is a bottom view thereof; and,

FIG. 14 is a front view similar to that of FIG. 9, but with the alternate article carrier illustrated in its open configuration. The broken lines shown in FIGS. 7 and 14 are for illustrative purposes only and form no part of the claimed design.
